UNITED STATES PATENT OFFICE.

WILLIAM JOSEPH ROGERS, OF TERRELL, TEXAS.

CHURN.

SPECIFICATION forming part of Letters Patent No. 317,019, dated May 5, 1885.

Application filed July 2, 1884. (No model.)

To all whom it may concern:

Be it known that I, WILLIAM J. ROGERS, a citizen of the United States, residing at Terrell, in the county of Kaufman and State of Texas, have invented a new and useful Churn-Motor, of which the following is a specification, reference being had to the accompanying drawings.

My invention relates to churn-motors; and it has for its object to provide a device of this character which shall be cheap and simple in its construction, durable in its use, and one that may be easily operated.

With these ends in view the invention consists in the improved construction and combinations of parts hereinafter fully described, and pointed out in the claim.

In the drawings, Figure 1 is a side elevation showing the actuating mechanism. Fig. 2 is a side elevation showing the dasher-shaft and the manner of connecting the same with the fly-wheel, and Fig. 3 is a transverse section through the fly-wheel shaft and crank-arm of the same.

In the accompanying drawings, in which like letters of reference indicate corresponding parts in all the figures, A represents the frame, which consists of the end standards, *a*, provided at their lower ends with foot-pieces *b*, braced by a bar, *c*. The end standards, *a*, are connected at their upper ends by means of strips *d* upon the upper side, and about midway of the length of which are provided brackets or boxes *f*. In these brackets or boxes *f* is journaled or mounted a shaft, *g*, carrying at one of its ends, outside the frame or sides of the frame, a fly-wheel, *B*, one or more of the arms of which may be provided with a screw-threaded opening, *h*, for the reception of a screw-threaded and headed wrist or crank pin, *i*.

C represents a lever, which is pivoted at the upper corner of the rear end of the frame to a block, *j*, secured thereto. This lever is provided with a longitudinal slot, *k*, of sufficient length to allow the pin of the fly-wheel to work from one end to the other of the same, the lever being held in position by the head of the pin. The forward end of

this lever extends beyond the front end of the frame, and is provided at said front end with a pivoted dasher, *D*, which may be of any preferred construction. The other end of the shaft *g* is screw-threaded, and upon said screw-threaded end is mounted a crank-arm, *E*, having a transverse screw-threaded opening, which is adapted to receive a set or thumb screw, which when tightened bears upon the shaft and prevents the crank-arm from turning upon said shaft.

To the front end of the frame, at or near the lower end thereof, is hinged a strip, *l*, the forward end of which is free, and rests in a recess, *m*, formed in the supporting-strip. In a slot at about the center of the strip or rod *l* is pivoted a rod, *m'*, which is connected at its other end to the crank-arm *E*. At the free end of the strip or rod *l* is pivoted in a slot thereof an operating rod or handle, *m''*.

The operation is as follows: Upon the treadle *l* being operated by the handle *m* motion is imparted to the rod *m'*, which is connected with the crank-arm, which in turn imparts motion to the shaft *g*, which turns the fly-wheel, which actuates the dasher by means of the connection before described.

It will be seen that, if desired, the handle *m* might be omitted and the machine operated by the treadle *l*, though the handle is preferably employed. It will also be seen that a churn-motor constructed in accordance with my invention is simple, may be manufactured and supplied at slight cost, and, further, that it is easy to operate.

In order to point out more clearly the advantages and scope of my invention, I would have it understood that I am aware of Patents No. 294,064, dated February 26, 1884; No. 217,263, dated July 8, 1879; No. 79,035, June 16, 1868, and do not seek to claim anything therein shown and described.

Having fully described my invention, what I claim as new, and desire to secure by Letters Patent, is—

The combination, with a suitable frame having a fly-wheel mounted in bearings thereof, and a wrist-pin on said fly-wheel, of the lever *C*, pivoted to the frame at one end, and

carrying a pivoted dasher at its other end, said lever having a slot or opening, *h*, to receive the wrist-pin, a crank-arm, a treadle pivoted to the frame at one end, and carrying a handle at its other end, and a rod connecting the treadle and crank-arm, substantially as set forth.

In testimony that I claim the foregoing as my

own I have hereto affixed my signature in presence of two witnesses.

WILLIAM JOSEPH ROGERS.
